UNITED STATES PATENT OFFICE.

JASPER BLACKBURN, OF WEBSTER GROVES, MISSOURI.

SHIFTING DEVICE.

Application filed July 2, 1928. Serial No. 289,815.

My invention relates to improvements in shifting devices, and has for its primary object a shifting device intended for sliding gear transmissions.

- 5 A further object is to construct a shifting device in which the usual shift lever projecting through the floor board of a motor vehicle is eliminated and by this arrangement the floor board is free and unobstructed.
- 10 A still further object is to construct a shifting device in which the shifting elements are operated by means of the clutch pedal and in which the shifting elements operate laterally of the transmission.
- 15 A still further object is to construct a shifting device in which the desired speed can be preselected and then upon the depression of the clutch pedal, the shifting accomplished. In this way there is no danger, and in fact no possibility of shifting gears while the clutch is in engagement.

In the drawings:

- Fig. 1 is a vertical longitudinal section of a sliding gear transmission showing the engine flywheel and clutch and the shifting elements in position.

Fig. 2 is a top plan view of my device with the floor boards of a motor vehicle and the transmission casing covering removed.

30 Fig. 3 is an enlarged fragmental view with parts in section showing the manner of preventing accidental rotation of the shifting element operating rod.

Fig. 4 is a fragmental end view of Fig. 3 looking in the direction of the arrow.

35 Fig. 5 is a side elevation of the bell crank used in operating the shifting element operating rod.

Figs. 6, 7, 8 and 9 are plan views of the shifting elements.

40 Fig. 10 is an end view of the shifting elements in assembled form.

Fig. 11 is a fragmental section taken on the line 11—11 of Fig. 10 and showing the shifting element operating rod in position.

45 Fig. 12 is a section taken on the line 12—12 of Fig. 11.

Fig. 13 is a diagrammatic view of the shifting elements when in neutral position.

50 Fig. 14 is a similar view showing the position of the reverse shifting element.

Fig. 15 is a similar view showing the position of the low speed shifting element.

Fig. 16 is a similar view showing the po-

sition of the second or intermediate speed element.

Fig. 17 is a similar view showing the position of the high speed shifting element.

Fig. 18 is a fragmental view with parts in section of the upper end of the preselecting rod.

Fig. 19 is a sectional view of the lower portion of the preselecting rod showing the manner in which the same is rocked back and forth.

Fig. 20 is a fragmental section of one of the shifter bars showing the position of the rollers thereon.

Fig. 21 is a fragmental perspective of that end of the shifting element operating rod which engages with the shifting element.

Fig. 22 is a fragmental view with parts in section of the means by which a step to step movement is imparted to the preselecting rod; and

Fig. 23 is a view of Fig. 22 with the preselecting rod removed and viewed in the direction of the arrow.

In the construction of my device 25 represents the transmission housing which is of ordinary construction. To this housing is attached the flywheel housing 26 in which the flywheel 27 and clutch 28 are located. The clutch 28 is, of course, splined on the shaft 29 in the usual manner so that it can be engaged and disengaged with the flywheel. The shaft 29 extends into the housing 25 and has on its end a gear 30. This gear meshes with the gear 31 on the counter-shaft 32. The gears 33 and 34 are also mounted on the counter-shaft 32 and are connected with the gear 31 so that all of these gears will turn simultaneously. The driven shaft 35 has one end mounted in the shaft 29. The other end 36 projects through the rear of the casing 25 and which is arranged for the reception of the usual universal joint. The shaft 35 is splined as at 37 and on the splined portion are mounted sliding gears 38 and 39. The gear 38 has a collar 40 projecting forwardly therefrom, which collar is provided with internal gear teeth. These teeth, however, are not shown as they are of the ordinary construction now used in standard transmis-

100 sions. The teeth are designed to engage with the teeth on the gear 30 for high speed. The gear 38 is provided with a grooved

collar 41 in which the shifter fork 42 is located. The gear wheel 39 has a similar collar 43 for the reception of the shifter fork 44.

The shifter fork 42 is mounted on a shifter bar 45 while the shifter fork 44 is mounted on a shifter bar 46. Each of the shifter bars has a roller 47 rotatably mounted on its upper face and a roller 48 on its lower face. These rollers project through openings in the shifting elements as will be hereinafter explained; two of these elements being located on top of the bars, and two on the lower. The construction of each of the shifter bars as to the rollers is identical.

Located within the housing 25 are gears 49 and 50 which comprise the reverse gearing of the transmission. The rear end of the transmission is also provided with a housing 51, which extends laterally across the housing 25 and in which the shifting elements are located, the reverse shifting element 52 being the lowest. On this is placed a first speed shifting element 53. On top of the first speed shifting element rest the shifter rods 45 and 46. Placed on the shifter rods is the high speed shifting element 54 and on top of the high speed shifting element is placed the second speed shifting element 55.

The high and second speed elements are provided with triangular-shaped openings 56 adjacent the forward end of the elements and with substantially Y shaped openings 57 toward the rear of the elements.

The rollers 47 on the shifter rods 45 extend into the openings 56 of both of these elements and the rollers 47 on the shifter rod 46 through the openings 57.

The first and reverse speed shifting elements are provided adjacent their forward ends with substantially Y shaped openings 58 and to the rear of these openings with triangular openings 59. The rollers 48 on the shifter rod 45 pass through the openings 58 in the plates 52 and 53 while the rollers 48 on the shifter rods 46 pass through the openings 59.

The plate 55 is provided at its forward edge 60 with an extension 61, which extension is provided with a down-turned lip 62. The plate 54 has its forward edge 63 provided with an extension 64 which is provided with a down-turned lip 65. The extension 64, however, is offset to one side of the center of the plate so that the lip 65 will lie next to the lip 62 and to the front side thereof.

The plate 53 has its edge 66 provided with an extension 67, which extension has an upturned lip 68. The extension 67 is so arranged that the lip 68 will lie toward the rear side of the lip 65.

The plate 52 has its edge 69 provided with an extension 70, which is provided with an up-turned lip 71. The extension 70 is in the

center of the edge and when the plates are assembled the lip 71 will be directly below the lip 65. This arrangement is clearly disclosed in Fig. 10.

The lips 65 and 71 are relatively short so as to permit the passage of the shifting element operating rod 72 therebetween as shown in Figs. 11 and 12.

The operating rod 72 is provided on its end with a tooth or projection 73 which is so arranged that it can be brought into contact with the desired lip and shift a preselected element.

The rod 72 also carries a collar 74, which collar is adapted to abut the outer edge or face of the various lips for the purpose of bringing the shifting element, which has been operated on, back to its starting position.

The operating rod 72 is supported in bearings 75, 76, and 77, the bearings 76 and 77 being relatively close together and receiving a sheave wheel 78 between them. The sheave wheel 78 is provided with keys 79, which fit in keyways 80 formed in the shaft 72. In this way the shaft 72 can have longitudinal movement in the sheave wheel but when the sheave wheel is rotated the operating rod will also rotate. This operation and its purpose will be explained in detail later.

The bearing 77 is also provided with keys 81, which are adapted to receive or pass into the keyways 80 when the shaft 72 is moved longitudinally and thus prevent accidental movement or rotation of the rod. The outer end 82 of the operating rod 72, however, is made cylindrical and of reduced diameter so that when the shaft 72 is in its starting position, it can be freely rotated but, as soon as longitudinal movement is imparted, it will be held against rotation.

The shaft 72 is also provided with a grooved collar 83, which receives the fork 84 of a bell crank lever 85. This bell crank lever is pivoted as at 86 and has on its short arm 87 an upstanding projection 88 through which a rod 89 is pivotally connected at 90 to the clutch lever 91. The rear end of the rod, however, is provided with a stop or nut 92, which, when the clutch is in engagement, will be at some distance to the rear of the projection 88. This is for the purpose of permitting the clutch to be disengaged a predetermined distance before operating the bell crank lever 85.

Between the collar 83 and bearing 76 is located a coil spring 93, which coil spring surrounds the shaft and has one end attached to the collar 83, which collar is tightly secured to the shaft 72, the other end of the spring being secured to the bearing 76. The purpose of the spring is primarily to keep the rod 72 in the position illustrated in Fig. 2 but, however, when the bell crank lever 85

is rocked, longitudinal movement is imparted to the shaft 72 and the spring compressed. This spring also prevents accidental movement of the bell crank lever 85 due to vibration of the machine.

Attached to the arm 87 of the bell crank lever 85 is a cable or chain 94 which passes around sheave wheels 95 and is connected to an arm 96 carried by the preselecting rod

- 10 97. This arm has also attached thereto a coil spring 98, the coil spring 98 being attached to any suitable point with the automobile body not shown and has a tendency to return the arm 96 to its normal position after it has 15 been pulled downward by the operation of the bell crank lever 85.

The arm 96 is provided with a boss 99 carrying a key 100, which key fits in a key-way extending in a longitudinal direction in 20 the preselecting rod 97.

The preselecting rod 97 is provided at its upper end with a handle 101 by means of which a rod can be pulled upward or can be rotated without rocking the bell crank 25 lever 85. This is for the purpose of altering the preselection without operating any of the shifting elements or clutch pedal.

Adjacent the handle 101 is a spring actuated dog 102 which is designed to come in 30 contact with spaced apart stops 103, 104 and 105. Adjacent the stops 103 and 104 are stops 106. The stops 103, 104 and 105 are provided with an opening 107 through which the rod 97 slidably passes. The openings in 35 the stops 103 and 104, however, are provided with a cutaway portion 108, which are of sufficient size to permit the dog 102 to pass therethrough.

The stops 106, however, are relatively narrow and not provided with a cutaway portion. This is for the reason that when the rod 97 is turned by means of the arm, the dog 102 can pass through the cutaway portion 108 and downward movement of the 40 rod is limited by the stop 106. However, as soon as the spring 98 turns the rod 97 to its original position, the dog 102 will pass above the stop 104 and permit the rod to move down to the stop 104 where the operation is repeated permitting the rod to move 45 downward and the dog to contact with the stop 105. As aforementioned, this stop is not provided with a cutaway portion as it is the utmost limit of downward movement of the rod 97. This downward movement is occasioned by a spring 109 which is preferably fastened to the floor board of the vehicle and exerts a downward pull on the rod. 50

To the lower end of the rod 97 is attached 60 a chain or cable 110, which passes around a sheave wheel 111 and then has its end wrapped around a sheave wheel 78. By pulling up on the rod 97 the chain or cable 110 is pulled and the shaft 72 rotated so as 65 to bring the tooth or projection 73 in align-

ment with one of the lips carried by the shifting elements and then upon movement of the clutch pedal longitudinal movement is imparted to the rod 72 through the bell crank lever. This movement will operate 70 a preselected shifting element moving the desired shifter bar.

During the pulling up of the rod 97, the cable or chain 110, of course, exerts a rotary movement on the sheave wheel and on the 75 rod 72 thus winding up or placing a rotary tension on the spring 93 and as the rod descends from stop to stop, this tension is exerted in the opposite way to rotate the rod 72 in the opposite direction thereby permitting automatic preselection.

It will also be noted from Fig. 2 and from Figs. 6, 7, 8 and 9 that the shifting elements 52, 53, 54 and 55 are provided with notches 112, which are adapted to be engaged by 80 spring actuated plungers 113, which are located in one side wall of the housing 51. The purpose of these plungers is to prevent accidental movement of any shifting elements not actuated by the operating rod 72. 85 This is to overcome any possibility of the friction between two adjacent plates partially moving one plate and thereby prevent complete shifting of the preselected gear.

The operation of my device is as follows: 90 It will be supposed that the machine or automobile is so positioned in the garage that its rear is at the outlet door. When in this position, of course, the transmission is in neutral and the engine can be started without 95 imparting any movement whatsoever to the vehicle. After the engine has been started, the operator grasps the handle 101 and pulls the rod 97 upward, the upward limit of the 100 rod being controlled by the key-way in the preselecting rod contacting with the lower end of the key 100. This upward pull will rotate the shaft 72 so that the dog 72 thereon will contact or be in position to contact with the upturned lip 71 of the extension 70 carried by the shifting element 52. Then a 105 forward movement of the clutch pedal will cause the tooth 73 to contact with the lip 71 and pull the plate 52 forward causing the inclined edge of the opening therein to contact with the roller 48 carried by the shifter rod 44 and move the same rearward thus causing the gear 39 to mesh with the gear 50. As soon as this has been done, the foot pedal is released which will cause the collar 74 to 110 contact with the lip 71 of the plate 52 and bring it back into its original position and the machine will start backward.

The handle is then released and the dog 115 120 125 130 135 140 145 150 155 160 165 170 175 180 185 190 195 200 205 210 215 220 225 230 235 240 245 250 255 260 265 270 275 280 285 290 295 300 305 310 After the vehicle has been backed a sufficient distance, the clutch lever is again depressed which, as before, will rock the bell crank lever on its pivot and impart longitudinal movement to the operating rod 72. The partial rotation, however, has now brought the tooth into such a position that it will contact with the lip 68 and upon the full depression of the clutch pedal, the plate 53 will be moved forward, imparting an opposite directional movement to the shift lever 46 through the roller 48 causing the gear wheel 49 to move forward and engage with the gear 34. The device is now in first speed forward.

After the vehicle has acquired a certain amount of momentum, the clutch pedal again is depressed, rocking the bell crank lever 85 and imparting longitudinal movement again to the operating rod 72 and simultaneously therewith also exerting a downward pull on the cable 94 pulling down the arm 96 so as to rotate the preselecting rod 97 to such a degree that the dog 102 will pass through the opening 108, which permits the rod 97 to slide downward to the next position or preselection. However, the shaft 72 can not turn because it has been moved longitudinally a sufficient distance to permit the keys 87 to engage the keyways 81 in the rod 72.

After the shifting has been completed, the clutch pedal is again released, which permits the rod to descent farther and engage with the stop 106. However, on account of the key-ways in the shaft 72 the tooth 73 cannot become disengaged from the lip but it must remain in that position until the collar 74 has brought that particular plate back into position. Then the shaft 72 can turn farther permitting the dog 102 to be raised up above the upper edge of the stop 106 so that the rod can move farther and engage with the stop 104.

The further movement of the rod 97, however, is prevented by reason of the fact that the dog 102 is now out of alignment with the opening 108 in that particular stop. This rotation will bring the tooth 73 into position to engage with the projection or lip 62 carried by the plate 55. Another depression of the clutch pedal will commence to move this plate forward causing the roller 47 carried by the shifter rod 45 to engage with the inclined edge of the opening 56 in this plate. This will draw back the shifter rod 45 bringing the gear 38 into mesh with the gear 33, which will be the second speed forward.

Then by again depressing the clutch pedal to its fullest extent, the tooth 73, which has been previously turned by the movements previously described, is brought into position so that it will contact with the lip 65 carried by the plate 54. This move-

ment will move the shifter rod 45 forward causing the internal gear 40 to mesh with the gear 30.

During these various movements just described, especially in shifting from reverse or low to either second or high, the inclined sides of the openings 57 in the plates 54 and 55 will contact with the roller 48 carried by the shifter rod 46 and shift this rod in such a manner that the gear controlled thereby will be in neutral position. In the same manner, if the vehicle has been shifted into high speed and the preselecting rod set for low speed, the inclined edges of the opening 57 in the plate 54 will contact with the roller 47 carried by the shifter rod 45 and draw the gear controlled by that rod out of its position before the inclined edge of the triangular opening, formed in the shifting element which has been preselected, will move the opposite shifter bar and thereby it will not be possible to shift one gear while another is in mesh. In other words, the shifting elements are so arranged that when one shifting element is moved, it not alone operates a preselected shifter bar but also will place another shifter bar, which has been previously moved, in operation so as to place the gear controlled thereby out of mesh and in neutral position.

I have found it desirable when going from one speed to another to make a slight pause after a previously engaged gear has been disengaged before operating the clutch pedal farther to engage the next preselected gear and in order to enable the operator to easily tell when this disengagement has taken place I have provided what I call a feeler. This feeler consists of a coil spring 114, its one end being secured in a lug 115 which is preferably fastened to the transmission housing although this end of the spring may be attached at any other convenient point.

Carried by the long arm of the bell crank lever 85 is a bracket 116 through which an eye bolt 117 extends. The opposite end of the spring 114 is secured in the eye of this bolt. The opposite end of the bolt is provided with a stop or nut 118 which is normally spaced away from the bracket 116 so that the bell crank lever can have a certain amount of movement before the nut 118 contacts with the bracket. As soon as this contact is made the coil spring 114 commences to expand thus placing additional tension on the bell crank lever and making it necessary to apply more power to the clutch pedal 91 thus warning the operator that the next engagement is about to commence. This feeler also assist in restoring the transmission to neutral since if the operator stops pushing on the clutch pedal at this period, that is as soon as this additional pressure is felt, the transmission will be in neutral.

and no gears in mesh. The lost motion is so arranged that the clutch pedal is depressed approximately half its distance before the additional tension commences and at such a time when all of the sliding gears are out of mesh.

By this arrangement the driver of the vehicle can readily ascertain when the device has passed into neutral after being previously in gear. Of course, with an experienced operator this feeler becomes unnecessary as he has learned by experience just how far to push the clutch pedal so as to shift the transmission into neutral.

Having fully described my invention, what I claim is:—

1. A shifting device comprising the combination with a sliding gear transmission, of a plurality of laterally movable superimposed shifting elements located to the rear of said transmission, shifter bars extending into said transmission and communicating with said shifting elements, and means operated by the clutch pedal of a motor vehicle for operating said shifting elements longitudinally in desired sequence.

2. A shifting device for sliding gear transmissions comprising a sliding gear transmission and its housing, laterally moving plates located at the rear of said housing, longitudinally moving shifter bars slidably carried by said housing and communicating with said shifter elements, a longitudinally operating rod provided on one end with a projection for contacting with a predetermined shifter element, said rod connected to and adapted to be moved longitudinally by the movement of a clutch pedal, and means for rotating said shifting element operating rod whereby said projection can be brought into operative contact with a predetermined shifting element.

3. A shifting device comprising a plurality of shifting elements provided with triangular and Y shaped openings, shifter bars located between certain of said shifting elements, rollers carried by said shifter rods and extending into said openings, means operated by the clutch pedal of a motor vehicle for imparting longitudinal movement to said shifting elements, said means including a preselecting means whereby a predetermined shifting element can be operated.

4. A shifting device comprising the combination with a sliding gear transmission, of a plurality of laterally movable shifting elements having openings, certain edges of

which are at an angle less than 90 degrees to the remaining edges located at one end of said transmission, shifter bars extending from said transmission and having projections thereon, said projections extending into the openings in said elements, means operated by the clutch pedal of a motor vehicle for operating said shifting elements, and means for moving said last mentioned means so as to preselect a desired shifting element.

5. A shifting device for sliding gear transmissions comprising a sliding gear transmission and its housing, of a plurality of superimposed shifting elements located at one end of said housing and movable laterally thereto, longitudinally moving shifter bars slidably carried by said housing and communicating with said shifter elements, a longitudinally moving operating rod provided at one end with means for contacting with a predetermined shifting element, means for operating said rod so as to preselect the shifting element desired, and means operated by the movement of the clutch pedal for imparting longitudinal movement to said operating rod so as to impart longitudinal movement to the preselected shifting element.

6. A shifting device comprising a plurality of superimposed shifting elements provided with openings, certain edges of which are arranged at an angle of less than 90 degrees to the remaining edges, shifter bars located between certain of said shifting elements, means carried by said shifter rods and extending into said openings, means operated by the clutch pedal of a motor vehicle for imparting longitudinal movement to said shifting elements, said means including a preselecting means whereby a predetermined shifting element can be operated.

7. A shifting device comprising the combination with a sliding gear transmission and its housing, of a plurality of superimposed laterally movable shifting elements carried by said housing, shifter bars located within said housing and communicating with said elements, means operated by the clutch pedal of a motor vehicle and connected to said shifting elements for operating the same laterally of the housing, and means for rotating said last mentioned means so as to preselect a desired shifting element.

In testimony whereof I have affixed my signature.

JASPER BLACKBURN.
